Inventor
T. C. Englehart,

By Clarence A. O'Brien
Attorney

UNITED STATES PATENT OFFICE.

THOMAS CAREY ENGLEHART, OF URBANA, OHIO.

SWIMMING DEVICE.

Application filed September 28, 1927. Serial No. 232,488.

This invention relates to new and useful improvements in swimming devices and aims to provide a device constructed for attachment to the hand of a swimmer so as to assist materially in the art of swimming. By reason of the present invention, the space between the fingers of a swimmer's hand is closed for obviously increasing the area of the water engaged during the back stroke of the hand, the device being so constructed as to feather through the water on the forward stroke so as to permit of the free forward hand action during swimming.

In carrying out the present invention there is provided a disc of heavy rubber or other suitable strong and waterproof material constructed for attachment to the hand and wrist of the swimmer and at the palm side of the hand. This disc is so reinforced at its edge to prevent the collapsing of the disc but yet to permit the same to fold upon itself in a direction away from the hand during the forward stroke of the hand through the water so that the disc may properly feather through the water and thereby prevent hindrance during the forward stroke. The said disc is prevented from folding upon itself during the backstroke by reason of the engagement of the same with the hand which is usually in extended position during the backstroke.

The invention further aims to provide simple means whereby the device may be rigidly associated with the hand.

In the drawing, wherein like reference characters indicate corresponding parts throughout both of the views,

Figure 1 is a plan view of the inner face of the device, partially broken away for disclosing the reinforcement around the edge thereof, the hand being disclosed in dotted lines for more clearly indicating the position of the device thereto.

Figure 2 is a detail section taken substantially upon the line 2-2 of Figure 1 shown in full line extended position and in dotted line folded position.

Now having particular reference to the drawings, my novel swimming device consists of a relatively large disc 5 of heavy rubber or other suitable flexible and waterproof material which disc is adapted to be disposed upon the palm of the hand as indicated by the dotted lines in Fig. 1 to close the spaces between the thumb and fingers when

in extended position to cause a greater displacement of water during the backstroke of the hand during swimming. At the palm side of this disc 5 the same is provided around its edge with a reinforcing ring 6 while formed at the edge of the disc is a tongue 7 adapted to extend over a portion of the wrist and to be secured thereto by a suitable strap 8 or any desirable fastening means. Furthermore, the palm side of this disc 5 is provided with a finger loop 9 of an elastic material for tight engagement over the index finger as disclosed in Figure 1.

Arranged between the disc 5 and the reinforcing ring 6 is a sectional wire ring the sections of which are designated by the reference characters 10-10. The ends of these sections are provided with interfitting loops 11 whereby pivotal connections are provided between the ends of said sections to permit the disc to be folded over upon itself as indicated at Fig. 2 by the dotted lines.

Obviously, when the device is applied to the hand the engagement of the same against the water on the backstroke of the hand will cause the same to assume the flat position indicated by full lines in Figure 2, being held in this position by its engagement with the palm of the hand so as to obviously cause a greater displacement of the water during the backstroke than is otherwise possible by the bare hand. During the forward stroke of the hand through the water, the said disc 5 will fold rearwardly so that the disc will feather through the water permitting of the free forward stroke of the hand during swimming.

In view of the foregoing description when considered in conjunction with the accompanying drawings, it will be apparent that I have provided a highly novel, simple and extremely efficient swimming device that is well adapted to all of the purposes heretofore designated, and even though I have herein shown and described the invention as consisting of certain detail structural elements, it is nevertheless to be understood that some changes may be made therein without affecting the spirit and scope of the appended claim.

Having thus described the invention, what I claim as new is:-

In a swimming device of the character described, a disc of relatively strong but flexible material adapted to be disposed upon the

palm of a hand, means for securing the disc at its center to the palm of the hand and reinforcing means around the edge of the disc, said reinforcing means consisting of a pair of ring sections and pivotal connections between the ends of the ring sections in alignment with the longitudinal extent of the wearer's middle finger to permit the disc to fold inwardly at its center so that the disc may feather through the water during the forward stroke of the hand through the water.

In testimony whereof I affix my signature.

THOMAS CAREY ENGLEHART
